UNITED STATES PATENT OFFICE.

THOMAS DANQUARD AND AUGUST YOUNG, OF NEW YORK, N. Y., ASSIGNEES TO AUTO PNEUMATIC ACTION COMPANY, A CORPORATION OF NEW YORK.

EXPRESSION MECHANISM FOR AUTOMATIC MUSICAL INSTRUMENTS.

Application filed September 16, 1918, Serial No. 254,198. Renewed June 26, 1922. Serial No. 570,939.

To all whom it may concern:

Be it known that we, THOMAS DANQUARD and AUGUST YOUNG, citizens of the United States, residing at New York, in the county of New York and State of New York, have invented a new and useful Expression Mechanism for Automatic Musical Instruments, of which the following is a specification.

10 This invention relates to expression mechanism for automatic musical instruments and more particularly to improvements in expression mechanism of the type shown and described in the prior patents to Welte et al., No. 1,008,291 issued November 7, 1911 and No. 1,225,902 issued May 15, 1917.

15 It is the general object of our invention to improve the details of construction and 20 to simplify the method of operation of expression mechanism of the type described, thereby securing increased economy of manufacture and increased reliability in operation.

25 With this general object in view, one feature of our invention relates to the provision of an improved and simplified self-contained double valve mechanism by which 30 different parts of the expression device may be controlled.

35 A further feature of our invention relates to the provision of valve mechanism which may be controlled from two separate tracker openings, or which may be entirely controlled from a single opening, so long only as the opening is uncovered.

40 Our invention further relates to an improved valve block for crescendo and decrescendo effects, to an improved manual cut-out mechanism, to an improved forte valve structure, and to other details, arrangements and combinations of parts which will be hereinafter described and 45 more particularly pointed out in the appended claims.

A preferred form of our invention is shown in the drawings in which

50 Fig. 1 is a diagrammatic view of a portion of an expression mechanism embodying our improvements, and

Fig. 2 is an enlarged detail view to be described.

Referring to the drawings we have in-

dicated at 10 a portion of a wind chest which is connected to the exhausting mechanism of the instrument. A pipe 11 leading from the striking pneumatics or actions of the instrument is connected through a chamber 12 to the interior of a governor pneumatic 13. A passage 14 is formed 55 through the movable leaf of the pneumatic 13 to the wind chest 10, said passage 14 being controlled by a swinging valve 15 pivoted at 16 to the movable leaf of the pneumatic, and partially closing the inner 60 end of the passage 14. A spring 17 tends to expand the pneumatic against the exhaust tension of the instrument. The valve 15 is connected by a link 18 to the movable leaf 19 of an expression pneumatic 20. The 65 mechanism thus far described is similar to that shown in the Welte patents, and forms no part of our invention.

To produce the forte effect, the pneumatic 20 must be quickly deflated, thereby lifting 75 the valve 15 and opening the passage 14 to its greatest extent. For this purpose we provide a pipe 21 leading from the expression pneumatic 20 to a valve structure A containing a chamber 22, a passage 23 connected to the exhaust of the instrument, a valve 24 controlling a port 25 opening from the passage 23 to the chamber 22, and a pouch or diaphragm 26 by which the valve 24 is controlled. A spring 27 is mounted 80 above the valve 24, the lower end of the spring engaging a collar 28 fixed on the upper end of the valve stem. A screw 29 forms an adjustable stop which limits the travel of the valve 24. The pouch 26 is 85 controlled by a tube 30 extending to a tracker opening 31, and the space below the pouch or diaphragm 26 is also connected by the usual bleed opening 32 to the exhaust chamber 23.

90 When the forte effect is desired a perforation in the music sheet uncovers the tracker opening 31, admitting atmosphere pressure which raises the diaphragm 26 and valve 24, thus connecting the exhaust chamber through the port 25 and chamber 22 to the tube 21 and expression pneumatic 20. The tube 21 being of relatively large size, the pneumatic is quickly deflated and the valve 15 is opened, producing a sudden 95 forte effect. The abruptness of this effect

may be determined by the adjusting screw 33 and the effect will continue so long as the tracker opening 31 is uncovered. The stop screw 29 limits the travel of the valve, and the spring 27 closes the valve as soon as the tracker opening is covered by the note sheet. The forte effect is thus controlled from a single tracker opening and is limited by the length of the perforation in the note sheet.

10 The expression may also be varied by changing the position of the usual loud pedal of the instrument, and for this purpose we provide the loud-pedal pneumatic 35 connected by a tube 36 to a valve chamber 37 in a valve mechanism B. A double valve 38 in the valve chamber 37 controls an upper port 39 connected to the atmosphere, and a lower port 40 connected to an exhaust chamber 41. A pouch 42 below the valve 38 covers a chamber 43 connected by a passage 44 to a port 45 covered by a cap 46 mounted on the lower side of a diaphragm 47. When the cap 46 is raised, the port 45 is connected to the atmosphere, and when 25 the port 45 is closed the passage 44 and chamber 43 are exhausted through the space surrounding a plunger 48 which extends into the exhaust passage 41. The plunger 48 is mounted on a diaphragm 50 covering 30 a chamber 51 connected by a tube 52 to a tracker opening 53.

When the opening 53 is uncovered, the diaphragm 50 is raised, pushing the plunger 48 upward and thereby lifting the cap 46 35 and opening the passage 44 to the atmosphere. The valve 38 is thus raised by atmospheric pressure on the diaphragm 42, connecting the exhaust to the pipe 36 and deflating the loud-pedal pneumatic 35, 40 which action continues so long as the tracker opening 53 is uncovered. When the opening 53 is closed the parts return quickly to normal position. In this way the loud-pedal mechanism is controlled from a single tracker opening, the pneumatic 35 being deflated so long as the opening is uncovered. This arrangement is useful when the instrument is used with music not specially prepared for controlling the Welte mechanism.

50 When, however, the usual Welte music is provided, it is desirable to control the loud pedal from two separate openings, by one of which it is thrown into action and by the other of which it is released. For 55 this purpose we connect the tube 54 at one end to the chamber 55 above the pouch or diaphragm 47, and at the other end to a valve chamber 56 in a valve mechanism C, said chamber containing a double valve 57 controlling a lower port to the exhaust passage 58 and an upper port connected to the atmosphere. At its lower end the valve stem of the valve 57 rests upon a diaphragm 59 controlled through a pipe 60 from a 60 tracker opening 61, the diaphragm chamber

having the usual bleed opening to the exhaust passage 58. At the upper end of the valve stem a head 62 is supported by a diaphragm 63 underlying a chamber 64 connected by a passage 65 and bleed opening 66 to the valve chamber 56. The passage 65 is also connected by a tube 67 to a tracker opening 68.

When the double valve 57 is raised by uncovering the tracker opening 61, the valve chamber 56 is connected to the exhaust and the cap 46 (valve mechanism B) is raised to admit atmospheric pressure to the passage 44, thus causing deflation of the loud-pedal pneumatic. At the same time the chamber 64 above the diaphragm 63 is connected to the exhaust through the bleed opening 66, thus maintaining the valve 57 in raised position even after the tracker opening 61 is closed. When, however, the tracker opening 68 is uncovered, air is admitted through the tube 67 and passage 65 to depress the diaphragm 63 and valve 57, thus closing the passage to the exhaust and again admitting atmospheric pressure to the chamber 56, whereby the passage 44 is closed and the loud-pedal pneumatic is restored to normal inflated position.

We have thus provided loud-pedal mechanism which may be controlled from a single tracker opening to operate so long as the opening is uncovered, or which may be controlled from two tracker openings, one of which controls deflation and the other inflation of the loud-pedal pneumatic.

The valve mechanism C above described, for alternately connecting the tube 54 to the exhaust or to the atmosphere, corresponds in function to the separate valve structures r^3 and r^4 in the first Welte patent. It will be seen that our improved structure, while performing all the functions of the earlier device, entirely omits the double valve q' together with all its connections. This simplification in valve control is a very important feature of our invention.

We will now describe certain improvements in the mechanism for securing crescendo and decrescendo effects. For this purpose a tube 70 is connected to a valve mechanism C', identical with the valve mechanism C above described. The mechanism C' is connected by pipes 71 and 72 to tracker openings 73 and 74. The effect of uncovering the opening 73 is to produce and maintain exhaust tension in the pipe 70, and the uncovering of the tracker opening 74 restores atmospheric pressure therein. The pipe 70 is connected to a branched passage 75, one branch of said passage leading through a bleeding port 76 to the expression pneumatic 20, and the other branch of said passage also leading to the pneumatic 20 but being controlled by an adjusting screw

77. This branched passage 75 is formed in a valve block 78 which also contains a second passage 79 leading from the pneumatic 20 to the atmosphere and controlled by a second adjusting screw 80.

With this construction there is a continuous leakage of air through the passage 79 to the pneumatic 20, and that there is also a small leakage of air through the branched passage 75 under normal conditions. When the tracker opening 73 is uncovered, however, the pipe 70 is connected to the exhaust and the pneumatic 20 is deflated through both branches of the passage 75, the combined area of these branches being sufficient to overcome the leakage through the passage 79. The relative effective area of passages 75 and 79 may be controlled by the adjusting screws 77 and 80.

20 We have found from experience that the adjustment of these passages is more readily accomplished when the bleeding port 76 of fixed area is provided.

For manual control of the expression we provide a hand lever 81 and a lost motion connection through a link 82 to the movable leaf 19 of the expression pneumatic 20. Whenever the hand control is used, it is desirable that the automatic control should be inoperative, and for this purpose we provide the pneumatic 20 with an atmosphere port 83 normally closed by a valve 84 adjustably mounted on the link 82. As soon as the hand lever 81 is moved to the left to vary the position of the leaf 19, the valve 84 will be raised, thus directly connecting the interior of the pneumatic 20 to the atmosphere, and rendering it impossible for any of the expression connections to exhaust

40 the pneumatic.

In Fig. 2 we have shown in detail the means by which we connect the lower end of a valve stem with the diaphragm by which it is lifted. For this purpose a block 90 is secured to, the upper face of the diaphragm, said block being provided with a recess within which the valve stem is freely movable. A layer of cloth or other suitable material 91 is fixed to the upper end of the block and is provided with a small opening to receive the valve stem. When the diaphragm is first raised it will press the block upward until the valve stem is seated in the bottom of the recess. The frictional engagement of the layer 91 will retain the parts in this relative position so that thereafter no lost motion between the stem and the diaphragm will be possible. In this manner we prevent lost motion without necessitating provision for accurate adjustment.

Having thus described our invention, it will be evident that changes and modifications can be made therein without departing from the spirit and scope of our invention.

tion as set forth in the claims, and we do not wish to be otherwise limited to the details herein disclosed, but what we do claim is—

1. In an expression device for automatic musical instruments, an expression pneumatic having an air passage opening therein, sheet-controlled valve mechanism effective to connect said passage to the exhaust or to the atmosphere, means to variably restrict said passage, a by-pass around said restricting means, said by-pass being connected to said pneumatic by a bleeding port, a second passage from said pneumatic to the atmosphere, and means to variably restrict said second passage. 70

2. In an automatic musical instrument having an air passage, controlling devices for said passage comprising a valve chamber connected to said air passage, exhaust and atmospheric connections to said chamber, a double valve controlling said connections, means including a tracker connection effective to cause said valve to be moved to establish exhaust connection to said chamber, a diaphragm connected to said double valve and additional to said means, a chamber having a portion covered by said diaphragm, a separate tracker connection to said portion of said diaphragm chamber, and a restricted passage from said valve 90 chamber to the same portion of said diaphragm chamber. 85

3. In an automatic musical instrument having an air passage, controlling devices for said passage comprising a valve chamber 100 connected to said air passage, exhaust and atmospheric connections to said chamber, a double valve controlling said connections, and means for positioning said valve, said means including a tracker connection having a restricted passage connected to the exhaust and a separate tracker connection having a restricted passage connected to the atmosphere. 105

4. In an automatic musical instrument 110 having an air passage, means to connect said passage to the exhaust or to the atmosphere and to maintain exhaust connection until released, said means including a tracker connection having a restricted passage connected to the exhaust, and a second separate tracker connection having a restricted passage connected to the atmosphere but exhausted when said first tracker connection is uncovered by a music sheet opening and thereafter maintained at exhaust tension until itself uncovered by a music sheet opening to connect said passage to the atmosphere. 115

5. In an automatic musical instrument 125 having an air passage, devices controlled from a tracker opening effective to connect said passage to the exhaust, devices controlled from a second tracker opening effective to connect said passage to the atmosphere. 130

- phere, and additional devices controlled from a single tracker opening effective to connect said passage to the exhaust so long only as said single opening is uncovered.
5. In an automatic musical instrument having an air passage, a diaphragm normally closing said passage, a chamber behind said diaphragm, devices controlled from two tracker openings for connecting said chamber to the exhaust or to the atmosphere, and additional means independent of said chamber and connected from a single tracker opening, effective to temporarily open said passage.
15. 6. In an automatic musical instrument having an air passage, a diaphragm normally closing said passage, a chamber behind said diaphragm, devices controlled from two tracker openings for connecting said chamber to the exhaust or to the atmosphere, and additional means independent of said chamber and connected from a single tracker opening, effective to temporarily open said passage.
10. 7. In an expression device for automatic musical instruments, an expression pneumatic, means to deflate said pneumatic manually, and a valve associated with said means by which the interior of said pneumatic is directly connected to the atmosphere when such manual deflation occurs.
15. 8. In an expression device for automatic musical instruments, an expression pneumatic having an atmosphere port, a hand lever, connections between said hand lever and the movable leaf of said pneumatic, said connections including a link having a lost motion connection to said movable leaf, and a valve adjustably secured to said link and effective to control said atmosphere port.
20. 9. In an automatic musical instrument, a valve chamber, an air passage through said chamber, a valve in said chamber for said
35. passage, said valve having an axial valve stem sheet controlled means to open said valve, a spring to close said valve, and an adjustable stop screw threaded in a fixed wall of said chamber, substantially aligned with said valve and effective to limit the 40 axial travel of said valve.
45. 10. In an automatic musical instrument, a pneumatic, tracker controlled means to connect said pneumatic to the exhaust so long as a certain tracker opening is uncovered, and separate tracker controlled devices effective to connect said pneumatic to the exhaust when a second tracker opening is momentarily uncovered and to retain said connection until a third tracker opening is 50 uncovered.
55. 11. In an automatic musical instrument, a valve chamber, connections from said chamber to the exhaust and to the atmosphere, a valve controlling said connections, said valve having a stem, and a diaphragm pneumatic effective to operate said valve, said stem being frictionally secured to said diaphragm, whereby said diaphragm is effective to push said valve positively in one 60 direction and to exert yielding tension to withdraw said valve in the opposite direction.

In testimony whereof we have hereunto affixed our signatures.

THOMAS DANQUARD.
AUGUST YOUNG.
